US00D447923B1

(12) **United States Design Patent** (10) Patent No.: **US D447,923 S**
 Taylor et al. (45) Date of Patent: **** Sep. 18, 2001**

(54) **COMBINATION CONTAINER OPENER**2186868 2/1987 (GB).
 2258227 7/1992 (GB).
 2291412 1/1996 (GB).(75) Inventors: **Curtis Taylor**, Chagrin Falls; **Jeffrey S. Plantz**, Seven Hills; **Nicholas E. Stanca**, Westlake, all of OH (US)

* cited by examiner

(73) Assignee: **Apex Medical Corporation**, Sioux Falls, SD (US)

Primary Examiner—Caron D. Veynar

(**) Term: **14 Years**

(74) Attorney, Agent, or Firm—Robert H. Earp, III

(21) Appl. No.: **29/074,916****CLAIM**(22) Filed: **Aug. 11, 1997**

The ornamental design for combination container opener, as shown and described.

(51) LOC (7) Cl. .... **07-99****DESCRIPTION**(52) U.S. Cl. **D8/40**

FIG. 1 is a top perspective view of the combination container opener, showing our new design;

(58) Field of Search D8/33-43; 7/151-156;
 30/400, 443, 450; 81/3.07, 3.09, 3.29, 3.4,
 3.41, 3.55, 3.48, 3.57

FIG. 2 is a bottom perspective view thereof;

(56) **References Cited**

FIG. 3 is a top plan view thereof;

U.S. PATENT DOCUMENTS

FIG. 4 is a left side elevation view, the right side elevation view being a mirror image thereof;
